HERMANN LEMP, OF HARTFORD, CONNECTICUT, ASSIGNOR TO THE SCHUYLER ELECTRIC MANUFACTURING COMPANY, OF CONNECTICUT.

ELECTRIC-ARC LAMP.

SPECIFICATION forming part of Letters Patent No. 369,456, dated September 6, 1887.

Application filed June 3, 1886. Serial No. 203,984. (No model.)

To all whom it may concern:

Be it known that I, HERMANN LEMP, a citizen of the United States, and a resident of Hartford, in the county of Hartford and State of Connecticut, have invented certain new and useful Electric-Arc Lamps, of which the following is a specification.

My invention relates to certain improvements in electric-arc lamps of the class in which the carbon is fed by the action of gravity or a spring, and is controlled in its movements by the operation of a clock-work, a clutch, or other mechanism, which is released at the same time that the carbon is fed, so that gravity or other force may move the carbon toward the other carbon.

The object of my invention is to provide a means whereby an arc may be re-formed in case the carbon may overfeed, so as to make contact with the opposite carbon.

The invention further relates to certain combinations of devices designed for application to that class of electric lamps in which the carbon is lifted to form the arc by one magnet whose parts retain a fixed position during operation of the lamp, while the feeding movement is under the control of a separately and independently-acting derived-circuit magnet.

The invention consists in the combination, with the main-circuit coil, by which the carbon-supporting lever is lifted and sustained normally in lifted position, of a shunt-circuit for throwing said magnet temporarily out of action, said shunt-circuit being governed by two circuit closers or controllers, one of which is closed when the main-circuit magnet is excited, while the other is open so long as the lamp burns with a normal arc, but is immediately closed in case the carbons come together. The latter circuit-controller is preferably governed by the action of a magnet whose coil is in a shunt around the carbons and whose armature or movable core serves to hold the points of the circuit-controller apart. In case, however, the carbons come together, the derived-circuit magnet loses its power and the circuit-controller governed thereby completes the shunt around the main-circuit magnet, the other circuit-controller governing such shunt being at such time closed.

My invention consists, also, in other details

of constructions and combinations of parts, that will be described, in connection with the accompanying drawing, and then specified in the claims.

The accompanying drawing illustrates in side elevation the parts of an electric lamp involved in carrying out my invention.

W indicates the upper-carbon carrier, which is geared to a feed-regulating mechanism consisting of a clock-work sustained on a suitable frame or lever, A, pivoted at D. Connected to said clock-work is the usual escapement-wheel provided with an escapement-lever, h, which serves to retard the downward movement of the carbon-carrier. The clock-work and retarding device may be of any desired construction, that herein illustrated being shown simply to illustrate the principle of the invention.

The lever A, which is pivoted at D, is actuated by an electro-magnet, M, whose coils are in the circuit to the carbons in any usual way. I have shown said magnet as provided with a movable core, B, connected to the lever A, though it is obvious that other forms of magnet might be employed.

The escapement-lever h is provided with an extension, p, adapted to engage with a detent-lever, f, which is pivoted at E to the frame carrying the clock-work of the lamp, and is provided with an armature, g, that is operated by an electro-magnet, S, whose coils are in a derived circuit around the carbons, as shown.

The detent-lever f is provided with a spring, i, which is connected at one end to an arm, m, rising from the lever A, and at the other end is connected to said detent-lever.

The detent-stop e, sustained from any suitable portion of the frame-work of the lamp, is placed in position opposite the end of lever f, so that when the lever A drops at its end connected to the core B the detent-lever f will engage with said stop and will release the escapement-lever h, thus allowing the carbon-carrier W to descend.

The electro-magnet S is provided with an armature-lever, K, which, when retracted, closes the contacts of a circuit-closer of any suitable construction. (Indicated at d.) When the magnet is active through the diversion of current to its coils by the formation of an arc,

the armature K is raised and circuit is broken at the contacts d.

In the same circuit controlled by contacts d are the contacts of another circuit-controller. 5 (Indicated at c.) The latter may consist of two springs, as shown, and is operated by the main-circuit magnet M in such way that the circuit shall be closed at c when said magnet is active.

1c To operate the circuit-controller e, I employ simply a rod or bar extending from the core B and arranged to impinge against the lower of the two springs at c. The circuit controlled by these two devices is a derived circuit or shunt around the coils of magnet M, as clearly indicated, the path of the current being from point a through contacts c, through contacts d, armature-lever K, and to a wire connecting with the upper carbon of the lamp 20 in any usual way. This circuit may be of any desired resistance, but should be sufficiently low to permit current to be diverted from the coils M to such extent that the core B will fall away when such circuit is closed.

25 The operation of the lamp would be as follows: When no current is passing, the lever A rests by its weight and the weight of the core B against any suitable stop, C, in which position the detent-lever f is disengaged from 30 the escapement h through contact of the lever with the stop e. The carbons are thus allowed to feed together, the wheel engaging with the carbon-carrier being free to revolve. When the branch around M is open at contacts c, the 35 current is turned on, and the lever A is lifted by the main-circuit magnet, thus withdrawing lever f from contact with stop e, and locking the escapement h, so that the upper carbon is lifted to form the arc. As the carbons separate, more current flows in the coils of derived-circuit magnet S, and the lever K is immediately lifted, inasmuch as its retractor is of low power. The path for any current around magnet M is thus opened at contacts d, and the 40 parts are so adjusted that this shall occur before the core of M rises sufficiently to close contact at c. The contacts c are finally closed as the core of M rises; but, as will be seen, the branch around M cannot close during the 45 starting of the lamp, and is left open until the power of S is abnormally weakened by the coming together of the carbons. The movement of the lever A also brings the armature g into proximity to the pole of the shunt-magnet S. The arc being thus formed, the feeding takes place by the operation of the lever f, actuated by the derived-circuit magnet S in obvious manner, the core of magnet B in the meantime maintaining its position and holding 50 the lever A up. If for any reason the carbons should come together, the current being short-circuited from the magnet S, the latter will 55 loose its hold on the armature K, which during normal operation is held up, and the latter will fall back, thus completing the branch around magnet M. The core B will thereupon fall, and the branch around the magnet M be-

ing ruptured at c, the core and lever A will be raised again, thus lifting the carbon-carrier. This action will be repeated until the arc has attained such a length that the armature K will be raised again, so as to rupture the branch at contacts d. It will be seen by this arrangement no current passes through the branch and the contacts of the circuit-controllers governing the same, excepting under the abnormal conditions which require the action of such devices in order to reseparate the carbons in case of overfeed, and even when this action occurs the contacts at which the brake takes place and where the spark forms are thus governed by the powerful main-circuit magnet. The devices also possess the additional advantage that, during the action of the main-circuit magnet in re-forming the arc in case of overfeed, a flashing or intermission of the light will occur at the carbon points through the repeated lifting actions, and notice will thus be given that the lamp is defective. It will also be observed that the power required to raise the armature K from position of rest will be less than that required to sustain, because in the latter position the armature is nearer the core; hence, although it might require contact of the carbons or very close approximation of the same before the magnet S would be weakened sufficiently to let go its armature, it would nevertheless require a considerable separation of the carbons to strengthen the magnet so far that its armature would be drawn up and put an end to the action of the magnet in raising the frame N in the operation of re-forming an arc.

I do not limit myself to any particular form of magnets or any particular constructions of circuit-controllers, the invention consisting in the combinations of magnets and circuits governed by said magnets in the manner hereinbefore described.

It is obvious that the invention is not limited to a lamp in which a clock-work is employed, but might be used for a lamp having other kinds of feed-controlling devices supported by lever A and engaging with the carbon-carrier.

What I claim as my invention is—

1. The combination, in an electric lamp, of a lifting-magnet, a circuit by which said magnet may be rendered inactive, and two circuit-controllers governing said circuit, one of said controllers being operated by said lifting-magnet and closed while the current flows through the carbons, while the other is governed by the action of current in a derived circuit around the carbons and is normally open while the arc is formed, but is closed through diversion of current from its governing-magnet when the carbons come together.

2. The combination, in an electric-arc lamp, of a main-circuit lifting-magnet for separating the carbons, a short circuit around the main-circuit magnet, a circuit-controller governing said circuit, a derived-circuit magnet acting on said circuit-controller during normal action of

- the lamp, in the manner described, so as to hold the same in proper position to keep the short circuit around the main-circuit magnet open, and a retractor adjusted below the normal power of said derived-circuit magnet. 5
3. The combination, in an electric-arc-lamp, of a main-circuit lifting-magnet for separating the carbons to form the arc, a circuit-controller governing the operation of said magnet, and a derived-circuit magnet operating on the circuit-controller, in the manner described, so as to hold the same during normal action of the lamp in proper position for keeping said main-circuit magnet in action, and a retractor 10 for moving the circuit-controller into proper position for throwing the main-circuit magnet out of action when current is shunted from the derived-circuit magnet by the coming together of the carbons, said retractor being adjusted 15 below the normal power of the derived-circuit magnet. 20
4. The combination, in an electric-arc-lamp, of a main-circuit lifting-magnet for holding the carbons apart, a derived-circuit magnet, a branch around the main-circuit magnet, and an armature-lever for the derived-circuit magnet, which lever closes said branch when on its back-stop. 25
5. The combination, with the main-circuit lifting-magnet, of a derived-circuit magnet, armature-lever therefor, a retractor adjusted to withdraw the armature when the carbons come together, and a back electrical contact-stop for the armature-lever connected to a branch around the main-circuit magnet. 30
6. The combination, with the main-circuit magnet and the derived-circuit magnet, of a branch around the main-circuit magnet and two circuit-controllers placed in series with one another in the branch, one governed by the main-circuit magnet and normally closed during action of the lamp and the other governed by the derived-circuit magnet and normally open during operation of the lamp. 40
7. The combination, in an electric-arc-lamp, of a carbon-supporting lever carrying a wheel gearing with the carbon, a detent-lever controlling the movement of said wheel and pivoted on the carbon-supporting lever, and a derived-circuit magnet whose armature is carried by said detent-lever. 45
8. The combination, in an electric-arc-lamp, of a carbon-supporting lever carrying a feed-regulating mechanism, a main-circuit magnet for actuating said lever to form the arc, a detent-lever supported on the first-named lever, and a derived-circuit magnet having an armature carried by the detent-lever, as and for the purpose described. 50
9. The combination, in an electric-arc-lamp, of a main-circuit magnet for forming the arc and a derived-circuit magnet having two armatures, a feed-controlling device governed by one of said armatures, a retractor for the same adjusted to permit the armature to move only on an abnormal increase of current in the derived-circuit magnet, controller-contacts governing the main-circuit magnet and operated by the second armature, and a retractor for the latter armature adjusted to permit the armature to be held up during normal action of the lamp. 55
10. The combination, in an electric lamp, of a detent-lever sustained on the carbon-supporting lever or frame, a fixed stop for disengaging said lever when the frame or lever is depressed, an armature carried by said detent-lever, and a derived-circuit magnet acting on said armature. 60
